UNITED STATES PATENT OFFICE.

HENRY W. BOND, JR., AND JAMES A. DAKIN, OF HOLYOKE, MASSACHUSETTS.

SHEET-STEAMING ATTACHMENT FOR CALENDERING-MACHINES.

SPECIFICATION forming part of Letters Patent No. 371,732, dated October 18, 1887.

Application filed March 7, 1887. Serial No. 229,918. (No model.)

To all whom it may concern:

Be it known that we, HENRY W. BOND, Jr., and JAMES A. DAKIN, citizens of the United States, residing at Holyoke, in the county of 5 Hampden and State of Massachusetts, have invented new and useful Improvements in Sheet-Steaming Attachments for Calendering-Machines, of which the following is a specification.

10 This invention relates to improvements in steaming attachments for paper-calendering machines, the object being to provide improved devices for distributing steam under the sheet-delivering devices of said machines, whereby 15 the frictional electricity with which the paper becomes charged in passing through the calender is dissipated, and the adhesion of one sheet to the other, occasioned by the presence of said electricity, is prevented; and the in- 20 vention consists in the peculiar construction and arrangement of said steam-distributing devices, all as hereinafter fully described, and pointed out in the claims.

In the drawings forming part of this specification, Figure 1 is a perspective view of two of the lower rolls of a paper-calendering machine, together with certain of the sheet-delivery tapes and guide-rolls connected therewith, having applied thereto steam-distributing devices constructed according to our invention. Fig. 2 is a side elevation, partly in section, of the steam-supply pipe and the steam-drum in which it is partially inclosed. Fig. 3 is a side elevation of one end of said steam-drum and of portions of the internal steam-supply pipe.

In the drawings, 3 and 4 indicate the rolls of the paper-calendering machine, and 5 the ordinary tapes between which sheets of paper 40 pass as they emerge from between the rolls of the calender, which tapes and the rolls over which said tapes pass, as shown in Fig. 1, are arranged in the ordinary way. The said tapes 5 serve the purpose of conveying the said 45 sheets of paper from the rolls of the calender onto any suitable table placed near the outer of said rolls.

The above-referred-to frictional electricity with which the sheets of paper become more 50 or less charged in passing through the calender occasions much inconvenience in placing

and arranging the sheets in uniform position in a pile on said table on account of their adhesion one to another; but by submitting them to the action of jets of steam, as below described, the said electricity is dissipated, and by the within-described improved devices for conducting the steam under the said delivery-tapes and there discharging it all danger of the escape of water with the steam, whereby 60 the paper would be wet and damaged, is entirely obviated.

A steam-supply pipe, 6, connected with any suitable steam-generator and having a stop-valve therein, as shown, extends parallel with 65 said roll 3 under the tapes 5, as shown in the drawings, and has a series of perforations in its under side, as shown in Fig. 2, for the escape of steam. The perforated portion of the steam-pipe 6 is inclosed in a cylindrical metallic case, 7, the upper side of which is provided with a series of perforations, as shown, 70 through which steam escapes and rises upward against sheets of paper which are carried away from said calender-rolls by said tapes, 75 the volume of steam ejected from the cylinder 7 being regulated by the stop-valve 8 in said steam-pipe. The under side of the cylinder 7 is so formed that it inclines from the ends of the cylinder to the center, as shown, and at 80 the latter-named point a tube, 9, is attached to the cylinder to carry off any water of condensation that may gather in the latter.

In calendering paper it often occurs that the number of sheets being run through varies, 85 and hence the superficial area against which steam is required to act is sometimes greater and sometimes less, and to provide for permitting more or less of the perforations in the cylinder 7 to discharge steam a cover or gate, 90 10, is arranged on one or both ends of the cylinder, to slide over the perforations therein to cover or uncover certain of them, said cover 10 having its borders engaging with the edges of suitable upturned strips secured on said 95 cylinder, as shown.

In operating the above-described paper-steaming devices the steam from the supply-pipe 6, escaping from the perforations in the under side thereof, is directed downward within the cylinder 7, and hence any water that may be carried by the pipe 6 is prevented

from being thrown upward and through the perforations in the cylinder onto the paper; but said water, owing to the said inclined form of the under side of the cylinder, is quickly directed into the drip-pipe 9 and carried off, while the steam with which said cylinder is filled escapes therefrom through its perforations and rises upward against the paper, as aforesaid.

10 The supply-pipe 6 may, if desired, be connected simply to one end of the cylinder 7 without being extended therein, as shown; but the distribution of steam is more uniform when arranged as shown in Fig. 2.

15 What we claim as our invention is—

1. Paper-steaming devices for calendering machines, consisting of a cylinder, as 7, having perforations in its upper side for the escape of steam, and having a drip-pipe connected thereto, combined with a steam-supply

pipe, as 6, extending longitudinally within said cylinder and having perforations therein through which steam escapes, substantially as set forth.

2. Paper-steaming devices for calendering- 25 machines, consisting of a cylinder, as 7, having perforations in its upper side for the escape of steam, a sliding gate, as 10, covering more or less of said perforations, and a drip-pipe connected therewith, combined with a 30 steam-supply pipe, as 6, extending into said cylinder and having perforations in its under side through which steam escapes, substantially as set forth.

HENRY W. BOND, JR.
JAMES A. DAKIN.
